REFRIGERATING APPARATUS

Filed Feb. 14, 1930

UNITED STATES PATENT OFFICE

EDWARD B. MALLORY, OF TENAFLY, NEW JERSEY, ASSIGNOR TO THE CLIMAX ENGINEERING COMPANY, OF CLINTON, IOWA, A CORPORATION OF DELAWARE

REFRIGERATING APPARATUS

Application filed February 14, 1930. Serial No. 428,326.

This invention relates to improvements in refrigerating apparatus and is herein illustrated as embodied in refrigerating apparatus of the sealed unit type, employing a compressor, condenser and evaporator. The invention has particularly to do with the matter of cooling the dome casing and the various parts of the mechanism contained therein, and also the cooling of the condenser and the compressed refrigerant contained within the condenser.

The invention relates to certain new and useful arrangements of the various parts of the apparatus including the dome casing and its contained mechanism, together with the condenser and also the structure of these associated parts whereby an apparatus is provided having high efficiency, with provision for cooling the apparatus by natural currents of air set up as convection currents created by the heat given up by the parts to be cooled to the air in contact or associated relation therewith.

The embodiment of the invention herein illustrated possesses the further advantage of being a compact unit of relatively simple construction and one which may be readily and cheaply manufactured, and further possesses the advantages whereby the various parts may be easily made and readily and quickly assembled by a simple and inexpensive operation.

A further characteristic of the disclosed embodiment is in its pleasing artistic appearance which enables its installation when it is desired, in open or in plain view, with a pleasing ornamental effect as distinguished from the unsightly and undesirable appearance of most machinery of this kind.

An important feature of the invention as here disclosed will appear from the following detail description to be that of providing for the passage of air, by means of natural convection currents over the various parts to be cooled whereby sufficient cooling air is brought into circulation and passed in contact therewith to remove and carry therefrom that amount of heat to be dissipated, requisite for the production of good and highly efficient performance in operation.

Attempts have been made heretofore to cool devices of this character by associating the condenser in surrounding relation to the dome and spaced therefrom, with the provision for a set of fins supported on and in contact with the dome serving as the support for the condenser coil. 55

The applicant after various tests, has found that better results can be obtained if separate and independent cooling fins are provided for the dome and the condenser respectively with no, or as little as possible, mental connection between these heated parts. This type of construction substantially eliminates the conveyance of heat 65 from the dome to the condenser coils by conduction travel, and permits each to be cooled independently of the other by the convection currents of the air. Apparatus of this construction constitutes the subject matter 70 of the applicant's co-pending application, Serial No. 374,015, filed June 27th, 1929. In the old type of device where the coil surrounded the dome with common supporting 75 fins, some of the heat of the dome was conveyed by conduction to the condenser coils which thereby placed the additional burden on the condenser of disposing of a portion at least, of the heat of the dome, as well as its own heat. Of course, an efficient operation requires that the condenser coils be capable of dissipating sufficient heat to cause the proper condensing effect of the refrigerating medium. 80

This invention represents a distinct departure from the type of unit in which a condenser coil surrounds the dome, my improved construction embodying an arrangement of parts which not only improves the operating characteristics of the refrigerating unit but readily adapts the unit to a design of pleasing appearance. The condenser is disposed below the lower confines of the dome whereby to actually remove these parts from any substantial heat transferring relationship. It 85 is found that there is substantially no heat transfer from the bottom of the casing by radiation, and by locating the condenser below the casing, it is out of the path of the heat rising from the dome and accordingly, is not 90 95 100

required to dissipate any of the dome heat. Further, the dome and condenser are provided with independent and separate sets of cooling fins, which are removed from each other.

By the arrangement of the present invention cooling fins of larger areas may be employed, with greater space to accommodate such fins and with a greater capacity for cooling air in contact with the dome and condenser, and their respective fins.

A further advantage of the present invention is that separate and independent bodies of cooling air are supplied to the dome and condenser respectively whereby each is cooled independently of the other to the extent of the full cooling capacity of the air.

Air currents established by convection are of relatively low velocity as compared with currents created by fans or similar means, consequently a distinct problem is presented in cooling by convection currents. The cooling to a large extent, is directly proportional to the radiating surface but unless the apparatus is made of large awkward form, difficulty has been encountered in providing the large fin area without making the air passages so small as to greatly retard the circulation. By placing the condenser with its fins below the casing, adequate space is provided for the fins of both the condenser and the dome with adequate space for circulating air.

This invention relates to refrigerating apparatus of the general type described and claimed in applicant's copending application Serial No. 428,324, filed February 14, 1930, but differs therefrom in that separate and independent air currents are provided for cooling the casing and the condenser respectively, all of which action may be accomplished by means of the construction hereinafter more fully described.

As above pointed out, the apparatus of this invention utilizes separate and distinct bodies of air for cooling the dome casing and the condenser respectively, and in this respect, it is somewhat like the invention described and claimed in applicant's copending application, Serial No. 428,325, filed February 14, 1930. However, the present invention is particularly characterized as one in which the air for cooling the dome is supplied from the bottom and passes upwardly through the space below the casing and up around the sides thereof.

Various other advantages not specifically mentioned are contemplated for the present invention, as will readily appear to one skilled in the art from the following detail description of an illustrative embodiment of the invention.

It is to be understood that the present disclosure is merely given by way of example

and is not to be considered as limiting the invention in any respect.

The scope of the invention may be determined from an understanding of the present disclosure and an appreciation of the principles incorporated therein and the advantages provided thereby.

Referring now to the drawing, it will be noted that:

Figure 1 is an elevational view in cross-section, disclosing a refrigerating apparatus constructed in accordance with the present invention;

Figure 2 is a plan view partly in cross-section taken on the line 2—2 of Figure 1 and looking in the direction of the arrows;

Figure 3 is a fragmentary cross-sectional plan view disclosing a modified form of fin construction around the dome casing of the apparatus;

Figure 4 is a fragmentary elevational view in cross-section of a modified form of condenser construction.

By referring to the drawing, it will be observed that the present invention is disclosed as embodied in a refrigerating apparatus comprising a casing 10 which may be of any suitable construction and which is sealed and serves as a housing for the motor 11 and compressor 12.

The casing 10 in the present disclosure constitutes a receptacle in the high side of the system for receiving the compressed refrigerating medium. This casing is entirely sealed from the atmosphere and as it constitutes the housing for the motor and compressor all possibilities of leaks are eliminated and the entire system is one which is completely sealed.

It will be noted that the casing 10 is of general dome construction preferably of metal having an annular groove 13 at its lower edge. Immediately above the groove 13 is a depression 14 which is adapted to receive the base plate 15, constituting the closing wall or bottom for the casing as well as the supporting base for the enclosed motor and compressor. The base plate is held by means of the ring 13' which fits within the groove 13 with the joint soldered, welded or otherwise sealed. The sealing means for the compression casing is described and claimed in the copending application of Robert L. Alexander and James R. McCallum, Serial No. 431,524 filed February 26, 1930.

Throughout the intermediate portion of the base plate 15, the machined surface 16 is provided of such construction that it serves as the lower wall portion of the compressor or pump cylinder. The cylindrical member 17 which also constitutes a portion of the cylinder is mounted on the base plate by means of the bolts 18 and on top of which the combined bearing and cylinder-plate 19 is mounted. This latter plate is also held by the bolts

18. The bearing 20 is provided preferably of relatively large size and of suitable construction to accommodate the shaft 21 which serves as a common shaft for the rotor 22 of the motor and the eccentric 23 of the pump. Mounted on the eccentric 23 is piston 24 all of usual construction whereby to develop a pumping action upon rotation of the shaft by the motor. The stator 25 of the motor is mounted in proper surrounding relationship to the rotor by means of the upstanding brackets 26 which may be of any suitable construction, extending upwardly from the upper plate 19, of the pump. This bracket can be formed of a plurality of independent parts attached to the plate 19, or as an annular support formed independently and secured to the plate or as an integral casting on the plate.

23 The above description is given for the purpose of illustrating the compact and simple internal motor and pump mechanism, which may be employed in the present apparatus. Further reference to the motor and compressor construction and arrangement will be omitted in this application, as these features constitute the subject matter of an invention of Robert L. Alexander and James R. McCallum, described and claimed in their co-pending applications, Serial No. 476,736 filed August 21, 1930 and Serial No. 484,537, filed September 26, 1930, and are only referred to here for the purpose of disclosing a complete assembly.

25 The discharge of the compressor is through the opening 27, which is closed by a leaf valve 28, directly into the atmosphere inside of the casing 10. The outlet for the compressed gases is through the pipe 29, the end of which terminates at the upper portion of 45 the casing and which extends downwardly and terminates in a coil 30, constituting the condenser for the apparatus.

45 By referring to the figures in the drawing, it will be noted that the casing is adapted to be mounted above the supporting surface for the apparatus by any suitable means, such as for instance, the resilient supporting legs 31, so that adequate space is provided below the base of the casing in which the 55 condenser may be accommodated without surrounding the casing. By employing the resilient legs here disclosed, greater quietness in operation is obtained which eliminates the desirability of mounting the motor and compressor construction on resilient supports within the casing. Although any suitable form of support may be utilized, the resilient support here shown comprises a series of posts 40, secured to the under side of the 60 base 15 of the casing and the opposed posts 41 carried by the base ring 42. The coil springs 43 are disposed around and in engagement with the posts whereby they are held in position and constitute the yielding support referred to.

The supporting surface referred to may be the top of a refrigerating cabinet 70, if it is desirable to mount the apparatus in this manner.

70 The present invention is not limited to the specific details of construction of the condenser; that is to say, whether the condenser be entirely outside the confines of the casing or not, provided, however, that the condenser is disposed so as to occupy space below the 75 bottom of the casing, whereby it is removed from lateral heat transferring relationship with the casing.

75 On this point, it may be pointed out that the heat transfer from the bottom of the 80 casing, by radiation, is relatively small and that heat conveyed by convection currents, passes upwardly from the dome and does not come near the condenser. The condenser in the present disclosure is shown 85 as composed of two concentrically arranged coils of pipes but obviously any arrangement of piping may be embodied if desired. However, it may be pointed out that the form of condenser and condenser assembly 90 disclosed in this application, have been found to be highly desirable and to present many 95 advantages from the commercial standpoint, as it may be easily manufactured and assembled as a separate unit and independently of the other apparatus, and be subsequently mounted with the other apparatus by a simple and cheap operation.

100 By reference to the right hand portion of Figure 2, it will be observed that the two 100 coils of pipe 32 and 33 respectfully, have a corrugated metal separator 34, placed therebetween. This separator is made up from metal which is relatively flexible so that it may be easily shaped to be inserted between the pipes in which position its natural resiliency tends to hold it in place and also assists in maintaining the coils in proper position. While in this position, the separator is also 110 maintained in intimate contact with the coils whereby it may receive heat from the coils 110 by conduction and serve as heat radiating fins therefor.

115 Additional fins 35 and 36 may be added inside and outside of the coils which are here 115 shown as single bent strips constructed similarly to the centrally disposed separator 34. These fins are added for the purpose of increasing the radiating surfaces and obviously 120 may be of any suitable construction, such as for instance, any of the constructions disclosed in the applicants co-pending applications referred to. In any case, these fins or strips may be secured to the pipes by welding or other suitable means so that the entire condenser may be made up and assembled as a unit independently of the other construction.

125 Surrounding the outer surface of the condenser, a shroud or skirt portion 37 is pro-

vided, preferably secured by welding or other suitable means, to the outer fins or strip 36. This shroud serves to enclose the condenser whereby the chimney effect is increased and also serves to improve the appearance of the machine.

For the purpose of cooling the dome, a plurality of fins 45 are provided thereon, extending radially and an enclosing shroud 46 10 is positioned around the fins as shown in Figure 1. This shroud provides enclosed chimneys with the fin construction whereby an increased convection draft is established for cooling the dome casing. The shroud 15 may be secured to the ends of the fins by means of welding the inner surface thereof to projections 47, formed on certain of the fins, or, it may be left unattached, that is to say, freely supported on the fins, whereby 20 ready removability is provided. The removability of the shroud in some instances, may prove desirable in order to facilitate cleaning of the fins for removal of dust and dirt which accumulates thereon. It has been 25 found that an accumulation of dust and dirt on the fins and dome surface, acts as a heat insulator and impairs the efficiency of the cooling action.

Depending from the lower edge of the 30 shroud 46, is a skirt portion 48 which may be attached in any suitable manner, that is to say, it may be supported from the shroud as shown, or by any other means, provided however, that it constitutes a partition be- 35 tween the condenser and the inner column of air serving to cool the dome casing and its fins.

This skirt is provided with an inclined 40 portion 49 which projects over the condenser and serves as a deflector plate to direct the air rising from the condenser outwardly and away from the shroud and dome fins. In the present illustration, the skirt is attached by means of the flange 49' having a beading 45 thereon which is snapped into engagement with and held by a similar flange 50 on the bottom of the shroud.

This form of connection permits the shroud to be readily removed as desired. The 50 skirt 48 has a depending portion 51 which extends downwardly from the inside of the condenser and serves as a support for the condenser. In this construction, the inner condenser fins 35 are welded or otherwise 55 secured to the skirt portion 51 as clearly shown in the drawing.

The skirt portion 51, the condenser and the outer condenser shroud 37 are so mounted and disposed, that a space is provided 60 therebeneath whereby to permit air to enter underneath and pass upwardly through the condenser and through the space below the dome casing and up around the sides of the dome and fins.

65 In the modification shown in Figure 3,

it will be observed that a slight modified form of dome fins are provided in that the fins are bent up from a single strip of metal 60. In this case, the portions 61 thereof are attached to the dome casing which give 70 a relatively large metal to metal contact for conveyance of heat to the fins by conduction. This form also offers a relatively large amount of metal area for exposure to the cooling drafts of air. In this form, several 75 of the U shape fin members disposed in spaced relation around the dome, may be provided with a lug 62 adapted to accommodate the screw 63, whereby the dome may be remov- 80 ably secured to the fins.

By referring to Figure 4, it will be observed that a slight modified form of condenser is provided in that the inner set 35 of condenser fins is eliminated and the inner coil 32, of the condenser, is wrapped directly 85 in contact with the depending skirt portion 51. In this case, the inner skirt portion 51 will serve as a radiating surface for dissipating some of the heat of the condenser.

By the construction of this invention, a central chimney is produced in the upper portion of which the casing with its enclosed motor and compressor is mounted so that heat of the casing induces a draft of convection currents upwardly for cooling the 95 casing.

Cooling means, such as fins are provided 100 on the casing for increasing the heat radiating surface and assisting in the formation of convection drafts. Accordingly, it is not in all cases necessary to provide the enclosing shroud around the casing and cooling fins hereinafter described, and illustrated in the drawing, as the chimney effect will be provided by the depending skirt in combination with the fins surrounding the dome.

This is particularly true for instance, with 110 the type of fins shown in Figure 3 which may be used with or without the enclosing shroud. This form always guarantees an adequate supply of air to the dome which comes up from the bottom from a region removed from the heated parts of the apparatus whereby to assure an adequate supply of cooled air. The air which reaches the dome, will not be drawn from any region which has been subjected to the heat of the condenser or other parts.

To assure this condition, the skirt portion 115 48 may be formed of insulating material whereby the air on the inside of the skirt will be insulated from the air on the exterior thereof. If insulating material is provided, it will maintain to a further degree, a separation of the bodies of air cooling the casing and condenser respectively, so that in neither instance, does one of these parts receive the heat of the other.

In the present disclosure, the air which 120 enters beneath the apparatus for cooling the 125 dome casing and condenser respectively, will be cooled by the fins surrounding the dome and the inner coil of the condenser.

casing and condenser, is drawn in underneath the condenser and skirt and then passes upwardly under the influence of the convection drafts, but obviously, any manner of supplying the air to the condenser and central chimney may be provided, that is to say, may be supplied directly upwardly through the base in which case, the machine can be mounted tightly on the supporting 10 surface.

The present disclosure shows the skirt portion as extending inwardly whereby the condenser is mounted in a manner to partially underlie the cooling fins of the dome casing. Whereas this formation makes for a more compact structure and permits the mounting of the condenser substantially within the confines of the overall dimension of the apparatus and in this regard, produces 15 a better appearing apparatus, it is conceivable that the shroud and skirt portion may be positioned in a vertical plane with the condenser mounted on the exterior of the lower portion thereof.

When the shroud and skirt are vertically disposed, the overhanging deflector surface 49 will be eliminated, but additional deflector surfaces may or may not be added, as desired. The main principle of the present 20 device, therefore, is that of providing a chimney which draws air from below and in which is induced a cooling draft for cooling the dome and the fin radiating surfaces thereof and further providing a condenser, outside 25 of said skirt or lower portion of the chimney whereby it may be cooled by an independent upward draft of cooling air which is entirely separated and independent from the air in the chimney serving to cool the casing.

In the event an insulating material is used, for the skirt construction, all possibility of 30 conveyance of heat from the condenser to the chimney air is eliminated.

In operation it will be apparent that the 35 dome becomes heated both by the operation of the motor and compressor contained therein and the heat of the compression of the compressed gases and also that the condenser becomes heated by the compressed gases passing therethrough.

An efficient operation requires that the dome heat be removed to an extent sufficient to avoid damage to the parts contained therein and also that the condenser be cooled sufficiently to cause a condensation of the compressed gases. It therefore appears that, although it is important to cool the dome casing, the cooling of the condenser deserves primary consideration to effect a satisfactory 40 performance of the apparatus.

With this in mind, it will appear that the heat of the condenser will establish a draft of convection air currents underneath the outer shroud 37 and upwardly in contact with 45 the surfaces thereof and thence outwardly as

developed by the surface 49 of the skirt. This provides a fresh and independent body of air for cooling the condenser.

It will also appear that the heat of the dome and surrounding fins will establish a 70 draft of convection currents inside of the shroud which draws air inwardly from the bottom up through the column located below the dome casing and inside of the depending skirt portion 51.

It is found that the draft established in the interior as induced by the dome heat, increases the draft of air under the apparatus and thereby accelerates the draft of air supplied to the condenser.

Another important factor is that of providing the bottom of the casing spaced above the supporting surface with the free circulation of air therebelow whereby a greater 80 cooling of the casing is provided. The circulation of air below the casing increases the cooling of the oil located in the bottom thereof.

It will thus appear that a construction is 90 here provided in which the condenser and the dome are maintained in such relative association that there is substantially no conveyance of heat from one of these parts to the other and furthermore, that each is provided with its own cooling fins of unusually large area, each having an abundance of free air surrounding the same in cooling relationship and finally the dome and the condenser with their respective cooling fins are each cooled by independent bodies of 95 fresh air.

In addition to the above advantages, the present invention provides a construction which is of compact, simple arrangement and one which produces a pleasing desirable appearance such that it might be mounted in plain view in instances where such mounting is desired.

The efficiency of an air cooled refrigerating machine is materially reduced by the collection of dirt and dust on the cooling surfaces as it forms a partial heat insulation to the action of the cooling currents. By providing radiating surfaces in the forms of fins, as herein illustrated, which are free from the coils of the condenser, greater access is provided for cleaning purposes and it will therefore be apparent that the cooling surfaces may be readily cleaned and the initial high efficiency of the machine easily maintained.

It will, of course, be understood that the machine of this invention may be mounted in any desired location, that is, entirely independently of the cabinet to be refrigerated or associated therewith, mounted on the top of the cabinet or in any conveniently located compartment therefor.

I claim:

1. A refrigerating apparatus of the character described comprising a motor and com- 130

- pressor in a sealed casing having cooling fins on said casing and a shroud enclosing said cooling fins and a condenser mounted on the exterior of said shroud.

5 2. A refrigerating apparatus of the character described comprising a motor and compressor in a sealed casing having cooling fins on said casing and a shroud depending below said fins and a condenser supported outside of said depending shroud. 70

10 3. A refrigerating apparatus of the character described comprising a motor and compressor in a sealed casing having means for supporting said casing spaced above a supporting surface, cooling fins on said casing and a depending shroud extending downwardly below said fins and a condenser mounted on the exterior of said depending shroud. 75

15 4. A refrigerating apparatus of the character described comprising a motor and compressor in a sealed casing having cooling fins on said casing and a shroud enclosing said fins and having a depending extension, and a condenser supported outside of said depending extension. 80

20 5. A refrigerating apparatus of the character described comprising a motor and compressor in a sealed casing having cooling fins on said casing, and a shroud depending below said fins and a condenser mounted on the exterior of said depending shroud, said shroud being constructed and arranged to permit air to enter through the bottom thereof and pass upwardly around the casing. 85

25 6. A refrigerating apparatus of the character described comprising a motor and compressor in a sealed casing having cooling fins on said casing, and a shroud depending below said fins and a condenser mounted on the exterior of said depending shroud, said shroud terminating short of the supporting surface for said apparatus whereby to leave a space for air to enter through the bottom thereof and pass upwardly around the casing. 90

30 7. A refrigerating apparatus of the character described comprising a motor and compressor in a sealed casing having means for supporting said casing spaced above a supporting surface, cooling fins on said casing and a depending shroud extending downwardly below said fins, and a condenser mounted on the exterior of said depending shroud, said shroud being constructed and arranged to permit air to enter through the bottom thereof and pass upwardly around the casing. 95

35 8. A refrigerating apparatus of the character described comprising a motor and compressor in a sealed casing having means for supporting said casing spaced above a supporting surface, cooling fins on said casing and a depending shroud extending downwardly below said fins and a condenser mounted on the exterior of said depending shroud. 100

40 9. A refrigerating apparatus of the character described comprising a motor and compressor in a sealed casing having means for supporting said casing with a space therebeneath, a shroud supported in spaced relation surrounding said casing having a depending portion extending below said casing and a condenser surrounding the exterior of said depending portion. 105

45 10. A refrigerating apparatus of the character described comprising a motor and compressor in a sealed casing having means for supporting said casing with a space therebeneath, a shroud supported in spaced relation surrounding said casing having a depending portion extending below said casing and a condenser mounted on the exterior thereof and a deflector portion extending between the lower end of said shroud and the upper end of said depending portion. 110

50 11. A refrigerating apparatus of the character described comprising a motor and compressor in a sealed casing having cooling fins on said casing with their outer edges collectively defining the side surface of a truncated cone, and a truncated conical shroud surrounding said casing and fins and supported by contact with at least some of said fins, and means for removably securing said shroud to said fins. 115

55 12. A refrigerating apparatus comprising a motor and compressor in a sealed casing and means supporting said casing with a space therebeneath, heat radiating means on said casing and a skirt, said skirt extending inwardly from the bottom outer edges of said heat radiating means and thence downwardly, and a condenser supported on the exterior of said downwardly extending portion of said skirt. 120

60 13. A refrigerating apparatus of the character described comprising a motor and compressor in a sealed casing having means supporting said casing with a space therebeneath, fins on said casing and a skirt extending inwardly from the outer lower portion of said fins and thence downwardly in spaced relation to said casing and a condenser mounted surrounding the outside of the downwardly extending portion of said skirt. 125

65 14. A refrigerating apparatus of the character described comprising a motor and compressor in a sealed casing having means supporting said casing with a space therebeneath, fins on said casing and a shroud surrounding said fins and a skirt extending inwardly from the outer lower portion of said shroud and thence downwardly and spaced from said casing and a condenser mounted on the out- 130

- side of the downwardly extending portion of said skirt.
15. A refrigerating apparatus of the character described comprising a motor and compressor in a sealed casing having means supporting said casing with a space therebeneath, fins on said casing, and a skirt extending inwardly from the outer lower portion of said fins and thence downwardly and spaced from said casing and a condenser mounted on the outside of the downwardly extending portion of said skirt and a second shroud surrounding said condenser. 5
16. A refrigerating apparatus of the character described comprising a motor and compressor in a sealed casing having means supporting said casing with a space therebeneath, fins on said casing and a shroud surrounding said fins and a skirt extending inwardly from the outer lower portion of said shroud and thence downwardly and spaced from said casing and a condenser mounted on the outside of the downwardly extending portion of said skirt, and a second shroud 10 surrounding said condenser. 20
17. A refrigerating apparatus of the character described comprising a motor and compressor in a sealed casing, having means for supporting said casing, fins on said casing and a shroud surrounding said fins and a skirt detachably attached to the lower edge of said shroud and a condenser supported on said skirt. 30
18. A refrigerating apparatus of the character described comprising a compressor and a motor in a sealed casing, spring supports for said casing and a condenser carried by said casing and disposed about said supports. 35
19. A refrigerating apparatus of the character described comprising a motor and compressor in a sealed casing, having resilient means for supporting said casing, and fins on said casing and a depending skirt supported by said casing through said fins and a condenser mounted on the outside of said skirt. 40
20. A refrigerating apparatus of the character described comprising a motor and compressor in a sealed casing, having resilient means for supporting said casing, and fins on said casing and a shroud surrounding said fins and a skirt depending from said shroud and a condenser mounted on said skirt. 50
21. A refrigerating apparatus of the character described comprising a motor and compressor in a sealed casing having cooling fins on said casing and a shroud depending below said fins and a condenser mounted on the exterior of said depending shroud. 55
22. A refrigerating apparatus of the character described comprising a motor and compressor in a sealed casing having cooling fins on said casing and a shroud enclosing said fins and having a depending extension, and a condenser mounted on the exterior of said 60 depending extension. 65
23. A refrigerating apparatus of the character described, having in combination a shroud constituting a substantially vertical chimney, a casing having a motor and compressor therein, mounted in the upper portion of said chimney and spaced from the sides thereof whereby the heat of said casing will induce an upward draft of cooling air around said casing sufficient to cool the casing during the operation of the machine, and a condenser mounted on the outside of said chimney. 70
24. A refrigerating apparatus of the character described, having in combination means constituting a chimney, a casing having a motor and compressor therein mounted in the upper portion of said chimney and spaced from the sides thereof whereby the heat of said casing will induce an upward draft of cooling air around said casing and a condenser mounted outside of the lower portion of said chimney below the plane of the bottom of said casing. 80
25. A refrigerating apparatus having in combination a motor and compressor in a sealed casing, means for supporting said casing with a space therebeneath, means constituting a chimney surrounding said casing and space below said casing and a condenser around the outside of said last named means, the portion of said last named means adjacent said condenser being formed of heat insulating material. 90
26. A refrigerating apparatus of the character described, having in combination means constituting a chimney, a casing having a motor and compressor therein mounted in the upper portion of said chimney and spaced from the sides thereof whereby the heat of said casing will induce an upward draft of cooling air around said casing and a condenser mounted outside of the lower portion of said chimney below the plane of the bottom of said casing, the portion of said chimney adjacent said condenser being formed of insulating material. 100
27. A refrigerating apparatus of the character described, having in combination means constituting a chimney, a casing having a motor and compressor therein mounted in the upper portion of said chimney and spaced from the sides thereof whereby the heat of said casing will induce an upward draft of cooling air around said casing and a condenser mounted outside of the lower portion of said chimney below the plane of the bottom of said casing, the portion of said chimney between said condenser and the casing and fins being formed of insulating material. 110
- In testimony whereof I affix my signature. 120
- EDWARD B. MALLORY. 125
